UNITED STATES PATENT OFFICE.

HERBERT MACKENZIE, OF SAUGUS, MASSACHUSETTS, ASSIGNOR OF THREE-FOURTHS TO JOHN N. MCKERRY, OF DEDHAM, MASSACHUSETTS, JOHN E. HALLETT, OF MALDEN, MASSACHUSETTS, AND THOMAS D. WALSH, OF BOSTON, MASSACHUSETTS.

NON-REFILLABLE BOTTLE.

SPECIFICATION forming part of Letters Patent No. 739,265, dated September 15, 1903.

Application filed May 25, 1903. Serial No. 158,616. (No model.)

To all whom it may concern:

Be it known that I, HERBERT MACKENZIE, of Saugus, in the county of Middlesex and State of Massachusetts, have invented certain new and useful Improvements in Non-Refillable Bottles, of which the following is a specification.

My invention has for its object to provide a bottle which when emptied of its contents cannot be refilled.

My invention is fully set forth in the following description, taken in connection with the accompanying drawings, and the novel features thereof are pointed out and clearly defined in the claims at the close of this specification.

In the drawings, Figure 1 is an elevation of a bottle embodying my invention, the upper portion thereof being in section. Fig. 2 is a sectional view of the upper portion of a bottle embodying my invention, inverted to show the position of the parts when the contents of the bottle are being emptied. Fig. 3 is an elevation, partly in section, with the movable parts of my invention removed therefrom. Figs. 4 and 5 are details hereinafter referred to. Fig. 6 is a section on line 6-6, Fig. 1.

Having reference to the drawings, the neck 30 of the bottle is shown at 1, said neck being of a sufficient length to afford room for the closure devices which are employed. The cork or stopper is shown at 2 and the body of the bottle at 3.

The body and neck and movable parts of the bottle may be formed from glass in the well-known manner.

The neck of the bottle is formed with one or more (preferably four) recesses 4, which are formed by outwardly curved or bulging portions 5 of the neck of the bottle. These recesses 4 are connected by an annular groove 6. (See Fig. 3.) Below the recesses 4 the interior of the neck of the bottle is formed 45 with an annular shoulder 7, and below this shoulder the interior walls of the neck of the bottle curve outwardly, as shown at 8. Below this point the walls curve inwardly at 81,

the said neck being correspondingly thickened and the opening within the neck being correspondingly diminished in cross-section until the neck opens into the body of the bottle at 9. (See Fig. 3.) The incurved walls 81 form a constricted passage between the neck and the body of the bottle, serving as a seat for the valve (shown at 10, Fig. 1) when the bottle is in an upright position.

Within the neck of the bottle and with its lower edge portion resting on the shoulder 7 is placed a substantially cylindrical device 60 (shown in Fig. 4) and which is designated 11. Cement is applied to the sides of the part 11, and the part is then placed within the neck of the bottle and against the shoulder 7 after the bottle has been filled and is thus securely fastened in place. The part 11 is provided near its upper end with lateral openings 12, which lie between the recesses 4 in the neck of the bottle. (See Figs. 1 and 6.) The lateral openings 12 project inwardly and open into a vertical opening 13', which is cylindrical in shape and in the center of which is the stem 14. The stem 14 projects downwardly below the lower conical end 15 of the part 11, and the lower end of the part 14 lies within the cavity of the valve 10. When the bottle is inverted, the valve 10 falls by gravity and by pressure of the liquid in the bottle onto the end of the stem 14 and away from the incurved walls 81, which constitute the seat of the valve. The stem 14 is preferably hollow and becomes filled with a portion of the contents of the bottle when the bottle is being emptied. When the bottle is again set in an upright position, the liquid within the hollow stem 14 serves as a weight to force the valve 10 back onto its seat against the incurved walls 81. The opening at the top of the neck of the bottle is closed by a stopper or cork in the usual manner.

Upon the sides of the stem 14 are two grooves 16, and across the bottom are two more grooves 17, connecting with the grooves 16. These grooves permit the liquid to reach the central cavity 13' of the stem 14, while at the same time the stem 14 affords a guiding-

bearing for the cup-shaped valve 10 during its movements.

When the bottle has been filled, the valve 10 is placed within the neck with its lower edge resting against the incurved walls or seat 81, and the cylindrical device 11 is then put in position with its lower edge resting against the shoulder 7 and is cemented firmly in position. The stopper or cork or the like 10 is then inserted.

The operation of the device is as follows: After the cork is withdrawn and the bottle has been inverted the parts assume the position shown in Fig. 2—that is, the valve 10 15 drops onto the end of the stem 14. The liquid contents of the bottle are then free to pass between the valve 10 and the incurved walls or seat 81, thence around the edges of the valve, up inside the valve, down the central 20 cylindrical opening 13', through the lateral openings 12, through the annular groove 6 to the recesses 4, thence out of the recesses 4 into the open neck of the bottle. During this operation a portion of the liquid may 25 flow into the hollow stem 14. As clearly shown in the drawings, the recess 4 extends beyond the cylindrical closure device 11. If now it be attempted to refill the bottle by placing it in an upright position and pouring 30 fluid into the neck, the valve 10, guided by the stem 14, will again be seated on the incurved walls or seat 81, and it will be impossible for the fluid to enter the body of the bottle. In the same way if fluid under pres- 35 sure is forced into the bottle while the latter is in an inverted position the valve 10 will be guided by the stem 14 and seated by pressure and the fluid will not be permitted to enter the body of the bottle.

40 My experience is, and I believe it to be the fact, that a bottle embodying my invention cannot be refilled. The cup-like shape of the valve 10, the cavity therein, the stem 14, and the incurved walls 81, on which the valve is 45 seated, render it impossible for the valve to get out of position regardless of the angle at which the bottle is held, while at the same time it may freely move to open or close the opening 9 between the body of the bottle and 50 the neck thereof.

What I claim is—

1. A non-refillable bottle having in the neck portion thereof an annular recess or groove and one or more intersecting recesses or 55 grooves to permit the passage of liquid, incurved walls below the said recesses or grooves forming a constricted opening in the neck, a cup-shaped valve seating upon said incurved walls, and a cylindrical device rigidly secured within the neck above said valve, and having openings therein connecting with said recesses or grooves in the neck, and also having a downwardly-projecting portion or stem engaging said valve when the bottle is 60

inverted, thereby preventing the said valve 65 from closing the opening in the said cylindrical device when the bottle is being emptied, substantially as described.

2. A non-refillable bottle having in the neck portion thereof an annular recess or groove 70 and one or more intersecting recesses or grooves to permit the passage of liquid, incurved walls below the said recesses or grooves forming a constricted opening in the neck, a cup-shaped valve seating upon said 75 incurved walls and a cylindrical device rigidly secured within the neck above said valve, and having radial horizontal openings therein and a vertical passage connecting said radial openings and the space directly above the 80 valve, whereby liquid poured into the neck may pass into the said valve and operate to seat the same and is thereby prevented from entering the bottle, substantially as described. 85

3. In a non-refillable bottle, the combination of a neck portion having a horizontal annular groove and one or more intersecting vertical passages therein, said neck also having a constricted passage at the point where 90 the neck joins the body of the bottle, a cup-shaped valve seating upon said constriction in the neck, and a cylindrical device having passages therein whereby the liquid poured into the neck is delivered within the cup-shaped valve and the said valve is thereby seated, said cylindrical device being provided also with a projection engaging the said valve when the bottle is inverted thereby preventing the said valve from closing the passage in 95 the cylindrical device, substantially as described. 100

4. A non-refillable bottle having rigidly secured in the neck portion thereof a cylindrical device having angular or tortuous openings 105 therethrough for the passage of liquid and a central cavity or recess which receives a portion of the liquid contents of the bottle when the latter is being emptied, incurved walls forming a constricted opening below said cylindrical device, a cup-shaped valve seating on said incurved walls to close said constricted opening, said valve being moved in one direction to permit the escape of the contents of the bottle by the pressure of the 110 liquid within the bottle and being moved in the opposite direction to close the bottle against the ingress of liquid by the pressure of the liquid contained in the said recess in the said cylindrical device, substantially as 115 described. 120

5. A non-refillable bottle, having in the neck portion thereof an annular recess or groove with one or more intersecting recesses or grooves to permit the passage of liquid, incurved walls below the said recesses or grooves forming a constricted opening in the neck, and a cup-shaped valve seating upon 125

said incurved walls, and also having secured within the neck above the valve a cylindrical device having in connection therewith a downwardly-projecting stem whereby the 5 valve is guided in its movements, the said device having lateral openings and a vertical opening connecting said lateral openings with the space above the valve, whereby liquid poured into the neck may pass into the valve

and operate to seat the same so as to prevent the liquid from entering the bottle.

In testimony whereof I have affixed my signature in presence of two witnesses.

HERBERT MACKENZIE.
